UNITED STATES PATENT OFFICE.

JOHN A. HOLLENBERGER, OF HAGERSTOWN, MARYLAND.

UMBRELLA.

SPECIFICATION forming part of Letters Patent No. 728,715, dated May 19, 1903.

Application filed February 20, 1903. Serial No. 144,301. (No model.)

To all whom it may concern:

Be it known that I, JOHN A. HOLLENBERGER, a citizen of the United States, residing at Hagerstown, in the county of Washington and State of Maryland, have invented certain new and useful Improvements in Umbrellas; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

This invention relates to new and useful improvements in umbrellas, and particularly in the provision of certain details pertaining to the manner of attaching the braces and the ribs of an umbrella, whereby the braces and 15 ribs may be removed and replaced at will; and in the present invention I dispense with all metallic or other fixed connections between the fingers upon the runner and the braces, also between the swiveled thimble and 20 ribs, and so construct the umbrella as to allow the thimble and the top connected thereto to rotate freely upon the stick.

The invention consists, further, in various details of construction and combinations and 25 arrangements of parts, which will be herein-after fully described, and then specifically defined in the appended claim.

My invention is clearly illustrated in the accompanying drawings, which, with the letters of reference marked thereon, form a part 30 of this application, and in which drawings—

Figure 1 is a sectional view through the top of an umbrella, showing in side elevation parts of the invention. Fig. 2 is a sectional view longitudinally through the runner to which the braces are detachably held. Fig. 3 is a sectional view through the swiveled thimble to which the top is held and to which the ribs are connected. Fig. 4 is a top plan 40 view of the runner. Fig. 5 is a sectional view vertically through the top of the runner. Fig. 6 is a sectional view through the sleeve on which the runner is mounted. Fig. 7 is a detail view of the blank from which the runner is made. Fig. 8 is a transverse sectional view 45 through the runner, showing the manner in which the braces are held in the slots therein.

Fig. 9 is a sectional view of a sleeve which supports the thimble or socket member engaged by the inner ends of the ribs. Fig. 10 55 is a sectional view of the thimble which receives the inner ends of the ribs. Fig. 11 is a bottom plan view of the thimble shown in Fig. 10. Fig. 12 is a view of the blank from which said thimble is formed, and Fig. 13 is 60 a detail view of one end of the brace.

Reference now being had to the details of the drawings by letter, A designates the stick of the umbrella, which in the present instance is shown as hollow and made, preferably, of 65 metal and provided with the usual spring-stop B, mounted in a recess in the stick. Mounted to have a longitudinal movement upon said stick is a sleeve C, which is longitudinally apertured at C' and has mounted on 70 one end thereof a thimble D, which, together with said sleeve, constitutes a runner. Said thimble D is stamped from a single piece of metal forming a star-shaped blank, (illustrated in Fig. 7 of the drawings,) the fingers 75 of which are bent into conical shape, forming the brace-engaging socket member (illustrated in Fig. 2 of the drawings) and in which slots are formed between each finger, the upper ends of said fingers adapted to contact 80 with the upper end of the sleeve, as shown, forming a closed slot. The portion of said thimble adjacent to the bottom of the slots is slightly cylindrical, as shown, forming a space for the reception of the flattened wing E at 85 the end of brace E', a detail of one of these braces being clearly shown in Fig. 13 of the drawings.

Each brace E' has its ends similarly formed with a wing, as described, and is pivotally connected at F with rib G. Mounted upon the stick and secured thereto by means of a pin J² is a sleeve I, having a flange I' at one end, and resting upon and having swiveled connection with said flanged portion is a thimble 90 J, which has a countersunk shoulder or seat J', Fig. 10 of the drawings, and the aperture in said thimble is adapted to receive the sleeve I, while the flange I' of said sleeve is designed to seat upon said shoulder J'. A 95 collar I² (shown in Figs. 1 and 3 of the drawings) has swiveled connection with the cylindrical portion I of said sleeve and rests upon the thimble J, said collar being provided to 100

prevent undue friction between the flanged sleeve I and the cover, and as the cover is fastened to the ribs in any suitable manner (not shown) it is obvious that the cover and ribs will turn with the thimble J. Said thimble J is formed from a single blank of metal and has radiating fingers, as shown in Fig. 12, previous to their being bent into the form illustrated in Fig. 1. In Fig. 1 the fingers are shown bent at right angles at points J³, forming, with the stick, closed slots J⁴, the inner walls of the fingers being slightly inclined, as shown clearly in Fig. 3 of the drawings. The inner ends of the ribs G have wings G' projecting from the ends thereof in a similar manner to the ends of the braces E', and in inserting the ribs in the slots J⁴ the rib is turned so that the wings will go in edgewise and the brace portion of the rib will turn the wing to a horizontal position to engage the inner walls of the fingers J³.

The winged ends of the braces E' are inserted in the slots of the thimble D in a similar manner as are the inner ends of the ribs inserted in the slots J⁴ of the thimble J, each rib G which is connected to the thimble J being inserted by twisting the rib a one-half revolution upon its longitudinal axis, the normal resiliency of the brace returning the wing to a horizontal position after being inserted in the slot.

From the foregoing it will be observed that by the provision of an umbrella having the improved means of attaching the braces and ribs as shown the ribs and braces can be

easily detached from the runner and swiveled thimble and easily and quickly replaced, and by the provision of the mechanism described I dispense entirely with fixed connections between the ribs and the thimble and also between the braces and the runner and make the entire frame carrying the top with swiveled connection to the stick. 40

While I have shown a particular construction of apparatus embodying my invention, 45 it will be understood that I may make alterations in the detailed construction of the same without departing from the spirit of my invention.

Having thus fully described my invention, 50 what I claim as new, and desire to secure by Letters Patent, is—

An umbrella comprising a stick, a runner-sleeve, a socket member fastened to said sleeve and having slots, braces having winged ends 55 positioned in said slots, a flanged sleeve fixed to the stick, a swiveled thimble provided with angled fingers and having a countersunk shoulder engaged by the flange of said fixed sleeve, the ends of the angled fingers of said swiveled thimble adapted to contact with the circumference of the stick and form closed slots, and ribs having winged ends engaging said angled slots, as set forth. 60

In testimony whereof I hereunto affix my 65 signature in presence of two witnesses.

JOHN A. HOLLENBERGER.
